Primary Examiner — Janice Hallmark(74) *Attorney, Agent, or Firm* — Ware, Fressola, Maguire & Barber LLP(57) **CLAIM**

We claim the ornamental design for a personal fan, as shown and described.

DESCRIPTION

FIG. 1 is a top perspective view of a personal fan showing our new design;

FIG. 2 is a front perspective view thereof, showing the personal fan in an alternate position of use;

FIG. 3 is a front elevational view showing the positions of cross-sectional views depicted in FIGS. 9 and 10;

FIG. 4 is a rear elevational view showing the position of a cross-sectional view depicted in FIG. 11;

FIG. 5 is a left side view thereof;

FIG. 6 is a right side view thereof;

FIG. 7 is a top view thereof;

FIG. 8 is a bottom view thereof;

FIG. 9 is a cross-sectional view taken along line 9-9 in FIG. 3;

FIG. 10 is a cross-sectional view taken along line 10-10 in FIG. 3; and,

FIG. 11 is a cross-sectional view taken along line 11-11 in FIG. 4.

The horizontal line surface shading in FIG. 3 is for the purpose of distinguishing between the open and solid areas of the front grill of the personal fan.
